UNITED STATES PATENT OFFICE.

FRIEZWILHELM, OF BERLIN-HALENSEE, AND KARL JOHANNES MÜLLER, OF BERLIN-GRUNEWALD, GERMANY; SAID WILHELM ASSIGNOR TO SAID MÜLLER.

LOUD-SPEAKING SOUND PRODUCER FOR TELEPHONES.

Application filed April 18, 1925, Serial No. 24,137, and in Germany May 12, 1924.

Our invention relates to a loud-speaking sound producer for telephones, particularly for the purposes of wireless telephony.

The object of our invention is to provide a sound producer reproducing tones and sounds of all kinds sonorously, clearly and in their natural timbre.

With this object in view, our invention consists in such an arrangement that the armature of a telephone receiver has an oscillation-transmitting connection with a resonance board and that the resonance board is forming a part of a resonating body.

Preferably the resonance board and the resonating body are made of wood. This arrangement has the advantage that by suitably proportioning the resonance board as well as the other parts of the resonating body the sound producer may reproduce both high and deep tones in such a manner that not only human speech, but also the different kinds of musical instruments may be brought to reproduction clearly and in their natural timbre and without disturbing secondary sounds.

The invention consists of structural characteristics and relative arrangement of elements to be hereinafter more fully described and particularly pointed out in the appended claims.

In the one sheet of drawings similar reference characters indicate the same parts in the two figures, in which

Figure 1 is a transverse longitudinal section partly in elevation of the invention, and

Figure 2 is a top plan view.

In the preferred form of the invention as shown in the drawings, the telephone electromagnet 1 is journaled upon a screw 40 rotatable in a seating 41, but is itself prevented from rotation with respect to the seating by means of a special transverse piece. The screw 40 rotatable in the seating 41 is provided with an exterior handle 42 by rotation of which the telephone electromagnet can be adjusted longitudinally of the sound producer.

The seating 41 is fastened by screws to the wooden ring 12 on which is also arranged the armature 5. The laminated ring 12 is secured to the floor 16 of the sound box, the cover of which is constituted by the sounding board 9. The sound box is preferably

constructed of wood, and a cross-piece 43 secured to the sounding board 9 is rigidly attached to and connected with the armature 5 by a pin 44, said pin 44 being straight and arranged normally to the plane of said sounding board 9. Thus the vibrations of the armature 5 produced by the electromagnet 1 are transmitted to the sounding board 9 the operation of which is enhanced by the sympathetic vibration of the sound box.

In order still further to enhance the scope of tones which can be reproduced by the sound producer without unwished secondary sounds, a second resonance board 45 is provided in the sound box. The pin 44 freely passes through this sounding board 45 and the two sounding boards 9 and 45 are connected by two bridges 46 if so desired, but this second resonance board 45 may be omitted in most cases.

The sound producer according to the invention need not have only a circular shape, but can also be quadrangular, quintangular, or of any other polyangular shape. It is obvious that various other embodiments may be constructed without departing from the spirit of our invention.

We claim:

1. In a combination with a telephone receiver, a resonance board, a pin rigidly attached to and connecting said resonance board with the armature of the said telephone receiver, said pin being straight and arranged normally to the plane of said resonance board, and a resonating body connected to said resonance board.

2. In combination with a telephone receiver, a resonance board, a cross piece on said resonance board, a pin rigidly attached to and connecting the armature of the telephone receiver with said cross piece on the resonance board, said pin being straight and arranged normally to the plane of said resonance board, and a resonating body connected to said resonance board.

3. In combination with a telephone receiver, a resonance board, a pin rigidly attached to and connecting said resonance board with the armature of the said telephone receiver, said pin being straight and arranged normally to the plane of said resonance board, a second resonance board having an oscillation transmitting connection with the first one, and a resonating

body connected to the said two resonance boards.

4. In combination with a telephone receiver, a resonance board, a cross-piece on said resonance board, a pin rigidly attached to and connecting the membrane of the telephone receiver with said cross-piece on the resonance board, said pin being straight and arranged normally to the plane of said resonance board, and a resonating body connected to said resonance board.

5. In combination with a telephone receiver, a resonance board, a membrane forming the armature of the telephone electro-

magnet and arranged parallel to said resonance board, means for securing an oscillation-transmitting and rigid attachment and connection of said membrane with said resonance board, a second resonance board having an oscillation-transmitting connection with the first one, and a resonating body connected to the said two resonance boards.

In testimony whereof we have affixed our signatures.

FRITZ WILHELM.

KARL JOHANNES MÜLLER.
